DIGGING TOOTH WITH NUT AND BOLT CONNECTING MEANS

Anthony F. Compagnoni, Chicago Heights, Ill., assignor
to American Brake Shoe Company, New York, N.Y., a
corporation of Delaware

Filed Aug. 13, 1962, Ser. No. 216,412
3 Claims. (Cl. 37—142)

This invention relates to digging teeth of a form to be 10
detachably secured to an adapter or like holder.

It is a common practice to provide dipper buckets, 15
trenchers, scrapers and like power-operated earth moving
equipment with digging teeth of a readily replaceable
nature. Usually, such replaceable teeth or so-called
points are associated with an adapter in turn rigidly se-
cured to the lip of the power-operated member. Such
teeth are sometimes detachably secured directly to the
aforesaid lip. Both arrangements are contemplated un-
der the present invention.

There is a common striving by workers skilled in this
art to develop an efficient arrangement enabling a point
to be removed and replaced with facility. Thus, where
such detachment and replacement are difficult to accom-
plish, there is a reluctance on the part of the shovel
operator to make the needed substitution for worn tooth.
As a consequence, the worn tooth is not replaced, and
the efficiency of the digging operation is diminished.

The tooth of the present invention is characterized by
a bolt extended laterally through the tooth or point and
the holder on which the tooth is detachably secured
thereby. The bolt is provided with a head recessed in a
substantially protected relation within one side wall of
the point, and the opposite end thereof is disposed in the
other side wall of the point, whereby opposite ends of
the bolt are effective to block the point against displace-
ment relative to the adapter shank or holder. The bolt
itself is retained against displacement by a portion there-
of threadedly connected to a nut located in a recess in
the adapter.

The arrangement of the present invention described
above represents an effective, inexpensive and readily
adopted means of detachably securing a digging point or
tooth to its holder, and such represents the primary ob-
ject of the present invention. Other objects of the present
invention are to enable the point to be adjusted on the
holder in a relatively simple fashion by providing for
a wedging action between a portion of the bolt and the
point; and to enable the point to be easily reversed or
inverted on its holder.

Other and further objects of the present invention will
be apparent from the following description and claims
and are illustrated in the accompanying drawing which,
by way of illustration, shows preferred embodiments of
the present invention and the principles thereof and what
is now considered to be the best mode contemplated for
applying these principles. Other embodiments of the in-
vention embodying the same or equivalent principles may
be used and structural changes may be made as desired
by those skilled in the art without departing from the
present invention and the purview of the appended claims.

In the drawings:

FIG. 1 is a side elevation of a tooth assembly con-
structed under and in accordance with the present inven-
tion;

FIG. 2 is a plan view of the tooth shown in FIG. 1,
partly in section;

FIG. 3 is a sectional view taken along the line 3—3
of FIG. 1 showing the point with the holder removed;

FIG. 4 is a fragmentary detail sectional view of a por-

2

tion of a modified tooth within the purview of the pres-
ent invention; and

FIG. 5 is a fragmentary detail sectional view similar
to FIG. 4 but showing a further modification.

The tooth assembly 10 illustrated in FIG. 1 includes
a tooth or point 11 detachably secured on a holder 12,
the latter in turn being adapted to be secured to the lip
of a power operated shovel, trencher or the like. It
may be noted, however, that the point 11 may be se-
cured directly to such lip as the holder for the tooth
in the manner that the tooth is secured to the holder or
adapter 12 as hereinafter described in detail. In other
words, the present invention may be utilized in either
a two-part tooth assembly including a point and an
adapter, or in a one-piece tooth secured directly to the
lip of a power-operated digging apparatus as the tooth
assembly.

The tooth 11 includes a pair of spaced upper and lower
walls 13 and 14 and spaced side walls 15 and 16 which,
in the rear section of the tooth or point 11, define a
generally V-shaped recess 18 configured complementary
to the tapered nose portion 21 of the holder 12 adapted
to extend into the tooth recess 18. The forward por-
tion of the point 11 tapers into an elongated relatively
narrow digging edge 22.

Teeth of the general kind under consideration are
commonly reversed on the holder 12 when one surface
thereof at the forward digging edge has been worn be-
yond an efficient condition. When the tooth is reversed,
the less worn side of the digging point comes into play,
and when this surface has been worn back sufficient,
the entire tooth is removed from the holder and is re-
placed by a fresh tooth. In other words, the holder is re-
capped.

In order to facilitate removal of the point 11 while
assuring a firm and effective fit on the adapter 12, the
tooth assembly under the present invention includes a
retaining bolt 25 having the shank thereof disposed in
an opening 26 which extends laterally through the nose
of the adapter 12.

The bolt 25 is of the Allen type and includes an en-
larged head 27 which fits neatly and substantially within
an opening 28 in the side wall 16 of the point 11. The
exposed or outwardly facing end of the head 27 is pro-
vided with the characteristic Allen-type socket 30 enabling
an Allen wrench to be entered therein incidental to
tightening and loosening the bolt 25.

The end 32 of the bolt 25 opposite the head 27 there-
of is seated in an opening 33 in the side wall 15 of the
point. It will therefore be seen that the head end 27 of
the bolt and the opposite end 32 thereof are effective in
corresponding openings in side walls of the tooth to hold
the latter on the adapter 12 in a rigid working relation-
ship.

The side wall of the adapter adjacent the wall 15 of
the point is provided with an hexagonal opening 35 af-
fording a complementary seat for a like nut 36. The nut
as thus seated is secured against rotation.

The bolt shank is threaded at the portion thereof cor-
responding to the nut 36, and the part are so dimensioned
and oriented as to assure that the end 32 of the bolt is well
seated within the opening at the side wall 15 of the tooth
when the bolt 25 has been effectively connected to the
nut 36.

Thus, in completing a positive lock between the point
and the adapter, the bolt 25 is passed through the opening
28 in the point into and through the opening 26 in the
adapter, through the nut 36 and into the opening 33 in the
side wall 15 of the point. While the arrangement is illus-
trated with the bolt on a horizontal axis, the same effects
can be achieved by having the bolt on a vertical axis.

A modified form of construction is illustrated in FIG. 4, specifically adapted to permit the point or cap to be pulled up on the adapter, at will, incidental to producing a tight fit between these parts. This is often necessitated by wearing down of the engaged upper and lower surfaces of the point and holder, especially when working in rocky areas. To this end, the openings identified above as 28 and 33 in the opposed walls of the point include tapered sides 28A and 33A. In the fully seated or extreme position, the head 27 of the bolt bears flush against the adjacent surface of the adapter as shown in FIG. 4, which characterizes the point or cap drawn upwardly on the holder a maximum extent. However, until this extreme condition is achieved, the head 27 of the bolt and the end 32 of the bolt bear on the wedge surfaces 28A and 33A, and while the point may be tight on the adapter at this time, there is yet enough take-up remaining to accommodate such further wearing down as may occur between the opposed surfaces of the point and adapter. Such take-up, it will be recognized, occurs relative to the nut as the "index" position on the holder 12.

It will be noted in the constructions described above that the opening in the tip in which the head of the bolt is disposed is of larger diameter in comparison to the opening in the tip in which the free threaded end of the bolt is disposed, this being in accordance with the enlarged dimension or diameter of the bolt head in comparison to the threaded end of reduced diameter. At the same time, however, relatively close or neat fits are involved in order to securely relate the tip to the holder. Nevertheless, the present invention can be easily incorporated in a tooth construction of the reversible type, that is, a tooth wherein the point can be removed from the holder after one side of the tip has been worn excessively, the point inverted and then re-applied to the holder to present the fresh or substantially unworn side.

Thus, referring to FIG. 5, this shows the principle of reversibility incorporated in a tooth of the kind shown in FIGS. 1 and 2, similar reference characters being used. Reversibility is accomplished by providing a recess or pocket 40 identical to the recess 35 at the side of the holder 12 opposite the recess 35 in which the securing nut 36 is located.

The pocket 40 is idle in the sense that spacer or filler ring 41 is disposed therein, this spacer having an opening 41A which enables the shank of the bolt to be passed freely therethrough to the extent that the head 27 of the bolt engages the outer face of the spacer 41. Then, when it is desired to reverse the point, the bolt 25, FIG. 5, is removed, the spacer 41 and the nut 36 are interchanged, and the point is inverted to disposed the opening 28 adjacent the recess 35 in which, incidentally, the spacer 41 has been relocated. Thereafter, the bolt is run into the nut 36, now in the pocket 40, to secure the parts together.

It will be seen that under the present invention the bolt 25 in effect pins the point to the adapter, and characteristically the bolt does not grip or squeeze the point, although by tapering the openings in the point it is possible to draw the point up on the adapter as may be required to eliminate slack therein during the course of gradual wear between the nose of the adapter and the opposed surfaces of the point. Additionally, it is possible

on the basis of the arrangement or equivalent shown in FIG. 5 to embody the present invention in a fully reversible tooth arrangement.

Hence, while I have illustrated and described preferred embodiments of the present invention, it is to be understood that these are capable of variation and modification, and I therefore do not wish to be limited to the precise details set forth, but desire to avail myself of such changes and alterations as fall within the purview of the following claims.

I claim:

1. A tooth assembly of the kind described including a holder and a point being detachably secured thereto; said point having first and second opposite walls defining a recess in which is received a complementary part of the holder; said holder having first and second walls on said complementary part and having a bore therethrough, said bore terminating in an enlarged seat in said second wall of said holder opposite the second wall of said point; said point having a first opening in said first wall aligned with said bore and a second, non-threaded opening in said second wall opposite said seat and aligned with said bore; a bolt having a head portion for seating within said first opening in said point and into engagement with said first wall of said holder, said head portion being closely dimensioned to the first opening in said point to prevent relative movement between said first walls of said holder and points, respectively; a nut seated in said seat in said holder and being wholly within said seat, said seat being dimensioned to prevent turning of said nut in said seat, and an end portion of said bolt extending into said non-threaded opening in said second wall of said point, said non-threaded opening being closely dimensioned to said bolt, engagement of said end portion with said non-threaded opening in said second wall preventing relative movement between said second walls of said point and holder, respectively.

2. A tooth assembly according to claim 1 wherein the openings in the point present tapered surfaces engageable by said head portion and said end portion of the bolt, respectively and wherein the head of the bolt has an opening therein for receiving a tool to turn said bolt relative to said nut.

3. A tooth assembly according to claim 1 wherein said point is reversible on said holder, said first side of said holder having a seat therein adapted to receive said nut when said point is reversed, and a spacer seated in the seat opposite said nut and in engagement with the head portion of said bolt.
